HEAT EXCHANGER

Addison Y. Gunter, Larchmont, and George B. Farkas, Jackson Heights, N. Y., assignors to American Locomotive Company, New York, N. Y., a corporation of New York

Application June 8, 1945, Serial No. 598,244

2 Claims. (Cl. 257—239)

1

This invention relates to new and useful improvements in heat exchangers.

An object of the present invention is to provide a heat exchanger having a shell openable at one end, and a cross fin tube-baffle assemblage in the shell removable therefrom through the openable end of the shell, for cleaning and repair, the baffles being thereafter removable from the fin-tube for cleaning, repair, replacement or adjustment.

Other and further objects of this invention will appear from the following description, the accompanying drawing and the appended claims.

Referring to the drawing forming a part of this application, Figure 1 is a foreshortened side view of an exchanger constructed in accordance with this invention, partly in central section, some of the fins of the tubes being indicated in dot-dash lines; Fig. 2 is an enlarged transverse section through the heat exchanger, taken on the line II—II of Fig. 3; Fig. 3 is a sectional view of a portion of the heat exchanger, taken on the line III—III of Fig. 2, the bars of the baffle assemblies being partly broken away and some of the fins of one of the tubes being indicated in dot-dash lines; Fig. 4 is a view similar to Fig. 2 of a heat exchanger constructed in accordance with a modification of this invention, taken on the line IV—IV of Fig. 5; Fig. 5 is a view similar to Fig. 3 taken on the line V—V of Fig. 4; and Fig. 6 is a perspective view of one baffle and a portion of the bar therefor of the embodiment of Figs. 4 and 5, the baffle being unattached and separated from the bar to better illustrate their construction.

The heat exchanger of Figs. 1—3 is indicated generally by the reference numeral 1. It includes a cylindrical shell 2 provided at its opposite ends with bolting flanges 3 and 4 respectively. The bolting flanges are each part of a member butt-welded to the end of the cylindrical pipe-like main part of the shell and the inside diameter of the members and main part are similar to the end that the entire inside of the shell from the outside of one bolting flange to the outside of the other bolting flange is similar, unobstructed and continuous.

The end of the shell adjacent the flange 3 is shown uncovered in the drawing. However, it will be understood that a cover of any usual type having a nozzle will be bolted on the flange 3. For the purposes of the present description, it will be assumed that this nozzle adjacent flange 3 will be the shell inlet nozzle. Therefore the open end

2

5 of the shell at flange 3 will be considered the inlet end of the shell.

The other end of the shell is closed by a head 6 bolted to the flange 4. The head 6 is sealed to the bolting flange 4 by a gasket 7 set in a recess 7a in the head and engaging an annular seat 7b integral with the flange 4. The head is provided with two diametrically aligned orifices 8 and 9, each threaded at its outer end for connection with a pipe and having grooves 10 at its inner end portion.

The shell is further provided with a nozzle 11, in the present instance an outlet nozzle, welded in an opening in the side wall of the shell adjacent flange 4. The shell is supported on channel beam supports 12 engaging the outer face of the shell. These supports 12 may rest on other similar supports of other exchangers of the instant type to form a battery of exchangers.

20 A U-tube member 13 is disposed in the shell. Its legs form two tubes 14 and 15 disposed at one end in the orifices 8 and 9 respectively and being secured therein by being swaged outwardly into the grooves 10 thereof. The other or inner ends 15 of the tubes 14 and 15 are connected by a U-bend 16. Each of the tubes 14 and 15 has bare end portions and therebetween cross fins 17. The cross fins are shown to be of the helical type but may be parallel, spaced strictly-transverse cross fins if desired.

25 The fins 17 are relatively short in radial height and are very much shorter in diameter than the diameter of the shell. The tubes 14 and 15 are in a diametral plane of the shell with the diametrically outermost edges of their fins in close proximity to diametrically opposite portions of the inner wall of the shell. A considerable space is provided between the tubes, that is, between the diametrically innermost edges of the fins of the tubes. Furthermore, while the fins are in close proximity with the shell in the diametral plane of the tubes, at right angles to this plane the shell wall is quite remote from the fins, providing two large spaces 18 and 19 on opposite sides 30 of the tubes. This is due to the fact that the shell and fins are circular in cross section and of widely different diameters.

A baffle assembly having two parts is associated with the tubes and is adapted to be removed from the shell with the tubes, as will later more fully appear. Thus the tubes and baffle assembly form a cross fin tube-baffle assemblage. Each baffle assembly part includes a bar 20, rectangular in cross section, provided with 35 aligned orifices 21 through its wide sides. Each

bar has permanently secured thereto, as by welding, soldering or brazing, on one wide side thereof, a series of thin sheet-like baffles 22. Each baffle is less than half a circle in shape. The bars are disposed in the space between the tubes with their inner faces opposed in spaced relation and with their baffles extending in opposite directions, the baffles on one bar being in space 18 and the baffles on the other bar being in space 19. The baffles bridge and engage the tubes and fit between fins of the tubes, the fins, if necessary, being bent to permit this positioning of the baffles. Thus the baffles hold the bars in spaced relation. The baffles of one bar are staggered in relation to the baffles of the other bar. The baffles are concentric with the inner wall of the shell and when disposed on the tubes have their outer curved edges in close proximity to the inner wall of the shell. The bars substantially fill the space between the tubes, preventing material axial flow of shell fluid through this space.

The baffles cause the shell fluid, which may be for instance cold oil, to flow through the shell from the inlet to the outlet in a path back and forth across the tubes. That is to say, the shell fluid flows crosswise of the tubes in the space between two baffles and then reverses in crosswise flow to flow back across the tubes in the next space between two baffles. This cross flow of the shell fluid back and forth across the tubes as it moves longitudinally of the shell provides for maximum heat exchange between the shell fluid and the fluid in the tubes, which may be for instance steam.

While the two baffle assembly parts would be held in place on the tubes by the close fit of the curved edges of the baffles and the inner wall of the shell, nevertheless positive means are provided for attaching the baffle assembly parts firmly to the tubes. This means constitutes a plurality of bolts 23 passing through aligned orifices 21, pulling the bars toward each other and making the straight edges of the baffles close tightly on the outer faces of the tubes, in effect clamping the tubes between the baffles of the two bars.

When it is desired to clean the spaces between the fins of the tubes or to repair any part of the tube-baffle assemblage or the inside of the shell, it is only necessary to unbolt the head 6 and pull it away from the flange 4, the tube-baffle assemblage moving with the head until it is out of the shell. Thus the present invention provides a heat exchanger permitting maintenance and repair of the various parts to be easily and economically executed. A shell drain 24, which is normally plugged, is formed in the shell flange 4.

The heat exchanger 1' shown in Figs. 4-6 is similar to the heat exchanger 1 of Figs. 1-3 but distinguishes therefrom in that the baffles 22' are not permanently attached to the bars 20' but are each provided with an orificed tab 25 secured to the correlated bar by means of a screw 26, the bar having threaded orifices 27 for receiving the screws 26. Other parts of this heat exchanger 1' corresponding to like parts of the heat exchanger 1 are indicated by like references with an accent added.

As shown in the drawing, and in accordance with preferred construction, each of the shells 70 contains only a single U-tube member. Thus a simple and efficient heat exchanger, lending itself to low cost cleaning, maintenance and repair, has been effected.

An important feature of the present invention 75

is that after the fin tube-baffle assemblage has been removed from the shell, the baffle assembly may be removed from the fin-tube for cleaning, repair or replacement. In the exchanger of Fig. 1, should it be desired to change the baffle spacing, the two baffle assembly parts may be replaced by other baffle assembly parts having a different number of baffles. The same applies to the exchanger of Fig. 4.

In the exchanger of Fig. 4, the bars may be provided with extra threaded orifices so that extra baffles may be bolted thereon if desired.

Where one bar only is used, or where the two bars when used engage each other, then the baffles need not rest on the tubes but may be slightly spaced therefrom.

While there have been hereinbefore described approved embodiments of this invention, it will be understood that many and various changes and modifications in form, arrangement of parts and details of construction thereof may be made without departing from the spirit of the invention, and that all such changes and modifications as fall within the scope of the appended claims are contemplated as a part of this invention.

The invention claimed and desired to be secured by Letters Patent is:

1. A heat exchanger comprising a cylindrical shell openable at one end and having an inlet and an outlet; a single series of two tubes in said shell disposed in a diametral plane thereof, each of said tubes having external cross fins, said tubes being disposed so that the diametrically outermost portions of said fins are adjacent diametrically opposed portions of said shell, the diameters of said fins being such in relation to the diameter of said shell that a space is provided between the fins of one of said tubes and the fins of the other of said tubes, and opposite wide spaces are provided between said fins and said shell inner wall on opposite sides of said plane; means connecting said tubes at their inner ends for series flow therethrough, the other ends of said tubes forming one an inlet and the other an outlet; a baffle assembly of two parts disposed in said shell, one part on each side of said diametral plane, each of said parts including a bar disposed in said space between said tubes and a plurality of spaced baffles secured to said bar, each of said baffles having an inner edge bridging and engaging said two tubes and fitting between fins thereof and a curved outer edge concentric with and adjacent the inner wall of said shell; and means connecting said bars, said bars substantially filling said space between said tubes, said baffles of one of said parts being disposed in one of said opposed spaces and staggered with relation to the baffles of the other of said parts disposed in the other of said opposed spaces for effecting a flow of shell fluid through said shell back and forth across said tubes, said tubes and baffle assembly being removable from said shell as a unit and said baffle assembly then being removable from said tubes.

2. A heat exchanger comprising a cylindrical shell openable at one end and having an inlet and an outlet; a single set of two tubes in said shell disposed in a diametral plane thereof, each of said tubes having external cross fins, said tubes being disposed so that the diametrically outermost portions of said fins are adjacent diametrically opposed portions of said shell, the diameters of said fins being such in relation to the diameter of said shell that a space is provided between the fins of one of said tubes and the fins of the other of

said tubes, and opposite wide spaces are provided between said fins and said shell inner wall on opposite sides of said plane; and a baffle assembly disposed in said shell, including a baffle support disposed in said space between said tubes and a plurality of spaced baffles secured to said support, each of said baffles having an inner edge extending over said two tubes and fitting between fins thereof and a curved outer edge concentric with and adjacent the inner wall of said shell, said support substantially filling said space between said tubes, some of said baffles being disposed in one of said opposed spaces and staggered with relation to the remainder of said baffles which are disposed in the other of said opposed spaces for effecting a flow of shell fluid through said shell back and forth across said

tubes, said tubes and baffle assembly being removable from said shell as a unit.
